UNITED STATES PATENT OFFICE

HENRY SCHMITT, OF TROY, NEW YORK

HEATER

Application filed September 10, 1929. Serial No. 391,564.

The present invention relates to a heating device.

More particularly, the invention relates to a device adapted for removable association with a kitchen range oven for effecting a continuous circulation of the air within the kitchen through the oven for effectively heating the kitchen as well as communicating adjacent rooms.

10 A primary object of the present invention is to provide a device adapted for removable association with a range oven for effecting a circulation of relatively cool air through the oven for quickly and uniformly heating the 15 atmosphere surrounding said range.

A further object of the invention is to provide a device adapted for removable association with a cooking range oven and which is so constructed as to provide a circulation of 20 air through said oven from adjacent the floor toward the ceiling of a room in which said oven is located for effectively heating the atmosphere within the room.

25 A still further object of the invention is to provide a device of the above noted character which is simple in construction, easily installed and removed, and which can be manufactured at relatively low cost.

With the above objects in view as well as 30 others that will become apparent during the course of the following disclosure, reference will be had to the accompanying drawing forming part of same and in which—

35 Figure 1 is a front elevational view of a device constructed in accordance with the present invention in a preferred embodiment thereof.

Figure 2 is a vertical sectional view of the 40 device taken substantially on a plane represented by line 2—2 in Figure 1.

Figure 3 is a side elevational view of the 45 device shown in operative relation with a cooking range oven, the range being indicated in dot and dash lines.

50 Referring to the drawings by reference characters in which like characters designate like parts, 11 designates the heating device as an entirety. The device 11 comprises inter-related, detachable, and relatively adjustable sections 12 and 13 which are preferably con-

structed of light sheet metal in any desired manner. The section 12 comprises a bottom 14, sides 15, a sloping top 16, a rear relatively shallow open end 17 and a front relatively deep closed end 18, the opposite ends 17 and 18 of substantially different depth being provided by the sloping or inclined top 16. The front end wall 18 is provided with an opening 21, which may be of a width equal to that of wall 18 and is preferably of the relative height indicated with the bottom thereof conforming to the inner surface of the bottom wall 14. The opening 21 may be provided in any suitable manner but preferably a portion of the material of wall 18 is beat inwardly 60 parallel with bottom wall 14 as indicated at 22 providing a guide for a purpose later referred to. The front end wall 18 projects laterally outwardly of opposite sides 15 providing flanges 23 for a purpose later described. 70 Each side wall 15 is provided with a hole 24 adjacent the junction of top wall 16 and front end wall 18 as indicated in Figures 2 and 3 for a purpose later described.

The section 13 is a substantially shallow L-shaped casing member of a width substantially equal to that of the length of opening 21 or the distance between side walls 15 of section 12. The section 13 comprises a portion 26 adapted for projection within section 12 through opening 21 in wall 18 thereof and adjustable relative to section 12, the portion 22 forming a guide therefor. The section 13 further comprises a portion 27 right angularly disposed relative to portion 26. The section 13 is open at opposite ends thereof or at the free ends of portions 26 and 27, the open end of portion 26 providing communication between sections 12 and 13 and the open end of portion 27 providing for the admission of air to be heated into section 13 and thence through section 12 in a manner hereinafter more fully described. The portion 27 of section 13 preferably has the front wall thereof cut away a substantial distance 95 from the free open end thereof as indicated at 29 for a purpose later described and the back and side walls of portion 27 opposite the cut away front wall portion are provided with a plurality of air admission holes 31. 100

The device hereinabove disclosed is adapted for removable association with a cooking range oven in the manner illustrated in Figure 3 in which R designates a cooking range which may be of any standard construction and O designates the baking oven thereof.

In the use of the device disclosed which is adapted for effecting a constant circulation of room air through the oven O for uniformly and quickly heating the air, the oven door is opened as indicated in Figure 3 and section 12 of the heating device 11 is inserted within the oven O with the bottom wall 14 thereof resting on the bottom wall of the oven and section 13 rests with the portion 26 thereof on the horizontally disposed inner wall of the oven, the portion 26 being adjustable relative to section 12 by loosely projecting portion 26 within opening 21 providing for fitting the device with ovens having different height doors, and the portion 27 of section 13 being disposed vertically with the end thereof preferably resting on the floor as indicated in Figure 3.

The section 12 of device 11 is of a width such that the side walls 15 thereof will fit within the side walls of oven O, and due to the existence of different width ovens, the flanges 23 which engage the oven externally thereof adjacent the margins of the door will assure complete closure of the oven from the bottom thereof to the top of front wall 18 of section 12.

The section 12 is formed of such length and height that in the applied position thereof a substantial space represented at 33 is provided between the inner end of section 12 and the back wall of oven O and a relatively shallow opening is provided above front wall 18 of section 12 the full width of oven O as represented at 34.

It will accordingly be seen that when the device 11 is in operative relation with oven O a natural air circulating course is provided through the right angularly disposed portions 26 and 27 of section 13, through section 12, and reversely through oven O in an upwardly deflected direction effected by the inclined outer wall of section 12.

In operation, with the device applied as indicated in Figure 3, the cooler air adjacent the floor will enter the open end of portion 27 through the cut away portion 29 and holes 31 and will flow upwardly and inwardly through horizontal portion 26 of section 13, into section 12. The air entering section 12 will for the most part flow through the shallow open rear end 17 thereof and outwardly of oven O through opening 34 in an upward course due to the angular outer wall of section 12. The air in circulating through oven O will be substantially heated and due to the continuous circulation of air in the manner indicated from adjacent the floor, through the heated oven and outwardly in an upward-

ly deflected direction into the room, the air within the room will be rapidly and uniformly heated by constantly admitting the colder air adjacent the floor into the heated oven and discharging same into the room.

Due to the formation of section 12 some heated air will become trapped in the upper front angular portion of section 12 which is permitted to escape into the room through holes 24 as indicated by the arrows in Figure 3.

The bottom wall 14 of heater section 12 may if desired be omitted thus giving a better thermal contact between the circulating air and the bottom of oven O.

While the portion 27 of heater section 13 preferably is of a length such that the free end thereof rests on the floor in applied position of device 11 as indicated in Figure 3, the portion 27 may be of such length that the free end thereof will be suspended slightly above the floor in which instance it will not be necessary to provide the cut away portion 29 and holes 31 but the air will directly enter the open end of the portion 27.

The sections 12 and 13 may be constructed of various sizes thus providing heating devices 11 adapted for different sized ovens. When it is desired to use the device, the oven door is opened as indicated in Figure 3 which is a common practice in cold mornings in order to rapidly heat the kitchen as well as adjoining communicating rooms and the device 11 is applied as indicated in Figure 3 with section 12 disposed within oven O and section 13 providing an air conduit from adjacent the floor to the front end of section 12 disposed with portion 26 thereof resting on the oven door and portion 27 thereof extending vertically toward the floor.

When the device is no longer required it is removed from oven O and stored away and due to the slidable connection between sections 12 and 13 substantially little storage space is required for the heating device.

From the foregoing disclosure it will be seen that a device is provided whereby a room can be quickly and uniformly heated by removable association of the device with an oven and that the device is simple in construction, cheap of manufacture and can be quickly installed or removed thus well adapting it to the use for which it is intended.

While I have disclosed but a single specific embodiment of my invention, such is to be considered as illustrative only and not restrictive since the scope of the invention is defined in the subjoined claims rather than by the foregoing specific disclosure.

What I claim and desire to secure by United States Letters Patent is:—

1. A heating device for removable connection with an oven comprising a casing section adapted for disposal within said oven; and an air conveying section communicating with

5 said first casing section; said conveying section providing a conduit for admitting air from a point substantially below said oven into said first casing section; and said first casing section provided with means for effecting an upward deflection of heated air from within said oven.

10 2. The construction defined in claim 1 in which said conveying section embodies angularly related portions; one of said portions adjustably connected with said first casing section and adapted for support on the door of said oven.

15 3. In combination with an oven; a casing section removably disposed in said oven; said casing section provided with a rear open end in spaced relation to the rear wall of said oven; said casing section provided with a closed front wall partially closing the opening into said oven for providing a substantially shallow opening into said oven adjacent the top thereof; said casing section provided with an inclined outer wall between said rear open end and said closed front wall; 20 and an air conveying section communicating with said first section for directing air from a point substantially below said oven into said casing.

25 4. The construction defined in claim 3 in which said conveying section comprises an L-shaped conduit member having one leg thereof slidably disposed in said casing section and the other leg thereof adapted to extend into proximity to the floor supporting 30 said oven.

35 5. A heating device for removable association with an oven comprising a hollow casing section adapted to be positioned in an oven; said casing section embodying sides, 40 a front wall provided with an opening adjacent the lower edge thereof; a rear relatively shallow open rear end, and an inclined top wall; said front wall provided with extensions beyond said sides which 45 extensions with said wall close the entrance to said oven except for a relatively narrow opening adjacent the top thereof; a second casing section provided with a portion adjustably communicating with said first casing section within said opening in said front wall and adapted to rest upon the open door of said oven and a second portion angularly disposed relatively to said first portion and extending vertically downwardly from said 50 first portion for conveying the lower cooler air into said oven through said first casing section; said air heated within said oven and passing therefrom over said inclined top wall out of said relatively narrow opening into 55 said oven.

60 6. The construction defined in claim 5 in which said first casing section is provided with holes in the sides thereof for the exit of heated air in the upper portion of said casing section.

7. The construction defined in claim 5 in which said second portion of said second casing section is provided with holes adjacent the free end thereof for the admission of air into said section.

75 In testimony whereof I affix my signature.
HENRY SCHMITT.
